UNITED STATES PATENT OFFICE.

EDWIN RUTHVEN SMITH, OF PARIS, TEXAS.

FOUNTAIN-PEN.

1,019,196.

Specification of Letters Patent.

Patented Mar. 5, 1912.

Application filed May 19, 1910. Serial No. 562,228.

To all whom it may concern:

Be it known that I, EDWIN R. SMITH, a citizen of the United States, residing at Paris, in the county of Lamar and State of Texas, have invented a new and useful Fountain-Pen, of which the following is a specification.

It is the object of this invention to provide a fountain pen, the contents of which may readily be fed manually, to the ink-applying portion of the pen.

Another object of the invention is to provide a novel means for manipulating the compressible reservoir in a fountain pen.

The drawings show typical embodiments merely, and it is to be understood that changes, properly falling within the scope of what is claimed may be made, without departing from the spirit of the invention.

In the drawings, —Figure 1 shows the invention in side elevation, a portion thereof being broken away; Fig. 2 is a longitudinal section, parts being shown in elevation; Fig. 3 is a fragmental top plan showing the feed tube flexed to one side, and positioned to fill the reservoir; Fig. 4 is a fragmental longitudinal section, showing the positions which certain of the parts of the device will assume when the reservoir is compressed prior to sucking the ink into the same; Fig. 5 is an elevation of the device whereby the nibs of the pen are connected; Fig. 6 is a detail perspective of the feed controlling rod; and Fig. 7 is a perspective of the supply tube.

Referring to Fig. 1 of the drawings for a general description of the device, it will be seen that the same comprises a handle, including a tubular body 1, to the end of which a ferrule 2 is secured. An ink-applying element 3 is inserted into the ferrule 2 the ink-applying element being supplied by means of a feed tube 4 communicating with a reservoir 6 located within the tubular body 1, the reservoir being adapted to be compressed, to force the ink through the feed tube 4, by means of a spring plate 5. A compression device is provided, the same protruding through one end of the tubular body 1. This compression device may be manipulated to compress the reservoir 6 to force the air out of the same, whereby, when the reservoir is released, the ink may be drawn into the same, through the feed tube 4. The ink-applying element may be of any form; in the present instance it is de-

picted as a right line pen of the sort commonly used by mechanical draftsmen, but it is obvious that another form of ink-applying element may be inserted into the handle so that the device may be employed as a writing pen of the ordinary sort.

In a more detailed description, and referring generally to all the figures of the drawings, it will be seen that the ink-applying element 3 consists of a shank 8, threaded upon its outer face, as denoted by the numeral 9. Fashioned integrally with the shank 8 or secured thereto in any desired manner, is a lower nib 10 and an upper nib 11. The end of the shank 8 is beveled as denoted by the numeral 12, the end of the tubular body 1 being correspondingly beveled, to receive the beveled end of the tubular body 1. The ferrule 2 is threaded upon the body 1, and adapted to engage the threaded portion 9 of the shank 8. Rotatably mounted upon the threaded portion 9 of the shank, is a nut 14, adapted to be brought into engagement with the end of the ferrule 2.

The spring plate 5 is forked at one end, as shown at 15, to engage a set screw 16, the latter being threaded into the upper nib 11. The intermediate portion of the spring plate 5 is arched away from the body portion of the pen, as at 17, the free end 19 of the spring plate being extended through an opening 18 in the body 1, and adapted, as seen most clearly in Fig. 2, to bear upon the compressible reservoir 6, the same being preferably fashioned from rubber.

Located within the tubular body 1 and extended longitudinally of the same, is a compression member 20, the extremity 21 of which is extended through the opening 22 in the end of the tubular body 1, there being a knob 23 or the like upon the exposed end of the part 21, whereby the compression member may be drawn to and fro, longitudinally, within the tubular body 1 of the pen. A lever 24 is provided, one end of which is pivoted at 25, to the intermediate portion of the compression member 20, the lever being pivoted intermediate its ends, as at 26, to the tubular body 1 of the pen. There is a longitudinally extended opening 27 in the body 1, in which the lever 24 is adapted to move, the free extremity of the lever being prolonged beyond the pivotal mounting 26 so that, as denoted by the numeral 28, it may outstand beyond the contour of the

body 1 under certain conditions which will be described in detail hereinafter. The end of the portion 28 of the lever is beveled, as at 29, and the body 1 is similarly beveled adjacent the end of the opening 27 therein.

These beveled portions of the lever and the body co-act to dispose the lever in such a position that it may serve as a closure for the opening 27 in which it is mounted.

10 In the shank 8 of the ink-applying element, there is an axial opening, into which one end of the feed tube 4 is inserted. This feed tube 4 extends outwardly from the handle portion of the pen, to a point adjacent the ends of the nibs 10 and 11. Slidably mounted in the feed tube 4 is a feed controlling device, the same being shown in the form of a rod 30, provided at its outer end with a rounded head 31, adapted to fit 15 in the cup shaped mouth 33 of the feed tube 4. Upon the inner end of the rod 30, there is a transversely disposed flat head 32, conforming approximately to the bore of the feed tube 4. The feed tube 4 is a resilient structure, and the rod 30 is likewise resilient.

The nibs 10 and 11 are preferably resilient, so that, when uncontrolled, they tend to spring apart. A screw 34 is passed 20 through the nibs 10 and 11, the screw being threaded into the nib 10, and slidable in the nib 11. As disclosed most clearly in Fig. 5, the end 35 of the screw 34 is flattened to fit 25 between the arms 36 depending from a circular head 37. Ears 41 upstand from the upper face of the head 37, the head being notched in one edge, as denoted by the numeral 40, as seen most clearly in Fig. 3. The flat portion 35 of the screw extends upwardly through the head 37, and is pivotally held between the ears 41. The lower edges of the arms 36 are curved as seen at 38, to fit within a depression 39, fashioned in the upper surface of the nib 11. When 40 the parts are disposed as seen in Figs. 1 and 2, the lower ends of the arms 36 will rest in the seats 39, holding the nibs 10 and 11 in proper relation. When, however, it is desired to separate the nibs 10 and 11, the 45 head 37 may be tilted, longitudinally of the screw 34, the flattened portion 35 of the screw passing out of the slot 40 in the head 37, the lower ends of the arms 36 being thus 50 swung out of the seats 39. By this operation, the nibs 10 and 11 will be set free, so that they may be separated for cleaning, or 55 for sharpening.

The operation of the device is as follows. The compressible reservoir 6 is 60 placed within the tubular body 1 and the shank 8 of the ink-applying element is rotated so that its threads 9 will engage the threads upon the interior of the ferrule 2. By this operation, the beveled portion 12 of 65 the shank 8 will be advanced into the open

end of the tubular body 1, ultimately engaging the open end of the reservoir 6, and binding the same between the beveled end 12 of the shank and the correspondingly beveled face upon the interior of the open end of the 70 tubular body 1. Thus, the open end of the reservoir 6 will be hermetically held between the shank 8 and the side wall of the body 1 of the pen. In order to hold the shank 8 within the body 1 against movement, the threaded jam nut 14 may be rotated to bear against the end of the ferrule 2. The device as thus far described may be considered to be as shown in Fig. 2.

When it is desired to fill the pen, the rounded head 31 of the rod 30 may be withdrawn slightly from the cup-shaped mouth 33 of the feed tube 4, thus opening the feed tube, it of course being understood that the diameter of the rod 30 is considerably 85 less than the diameter of the bore of the feed tube.

Referring to Fig. 3, it will be seen that the feed tube 4 and the rod 30 may then be flexed laterally. The free end of the feed 90 tube 4 may then be inserted into an ink-well, or other source of supply, the ends of the nibs 10 and 11 being positioned to one side, and out of the ink-supply. The button 23 may then be seized, causing the compression member 20 to move longitudinally, the lever 24 tilting from the position shown in Fig. 2 to that shown in Fig. 4. The compression member 20 will be thrust against the reservoir 6, compressing the same and forcing the air from it. When the button 23 is released, the resiliency of the reservoir 6 will cause the compression member 20 to move into the position shown in Fig. 2, the ink being sucked through the feed tube 4 into 105 the reservoir. The beveled portion 29 of the lever 24 of the body 1 co-act, so that when the parts are in the positions shown in Fig. 2, the lever 24 will be maintained in alignment with the side wall of the body 1, 110 completely closing the opening 27 in which the lever 24 moves. At this point it may profitably be stated that it is not necessary to manipulate the button 23 in order to fill the pen. If desired, the portion 28 of the 115 lever 4 may be engaged by the finger nail of the operator, or otherwise, and tilted from the position shown in Fig. 2 to that shown in Fig. 4, the compression member 20 thus being operated, without recourse to 120 the button 23.

When the device is in use, the ink will be 125 expelled from the feed tube 4 of the pen onto the nibs 10 and 11, by pressing the curved portion 17 of the spring plate 5 with the fingers, the end 19 of the spring plate thus being thrust against the reservoir 6, compressing the same slightly, and expelling a portion of the contents thereof. Obviously, by manipulating the spring plate 5, 130

the reservoir may be compressed to expel the air, and to suck the ink through feed tube 4; and likewise, the elements 23 and 28 may be manipulated to expel the ink from 5 the reservoir 6. These operations are desirable only under peculiar conditions arising in the use of the pen. The normal function of the spring plate 5 is to expel the ink, and the normal functions of the parts 23 10 and 28 are to expel the air from the reservoir 6 prior to the filling of the same with ink. Should it be desired to separate the nibs 10 and 11, the head 37 may be swung upon its pivotal mounting, so that the 15 extremities of the arms 36 no longer bear upon the nib 11. This operation, it should be understood, takes place without rotating the screw 34 in the slightest degree. Thus, the nibs may be spaced apart, cleaned, and 20 brought into close relation again, the space between the free ends of the nibs 10 and 11 remaining unaltered. Thus, a draftsman, finding in the middle of a line, that his ink is not flowing properly, may space the 25 nibs 10 and 11 apart, clean them, and return them to their original positions, the line being continued without any variation in the width thereof. The rounded head 31 upon the end of the rod 30 serves as a closure, partial or total, for the feed tube 4; and by sliding the rod 30 to and fro in the feed tube, the flat head 22 may be made to scrape the bore of the feed tube, removing therefrom any sediment or hardened ink which 30 may have accumulated.

Having thus described the invention what is claimed is:—

1. A fountain pen structure embodying a handle having an opening in its side wall; a 40 compressible reservoir in the handle; and a member protruding through the opening

and extended longitudinally of the handle, upon both sides of the opening, said member being bent where it passes through the opening, to permit the member to move in the 45 opening, transversely of the handle, and to define a shoulder in said member, adapted to engage one wall of the opening, to limit the movement of said member longitudinally of the reservoir. 50

2. A fountain pen structure embodying a handle provided with an opening, an ink applying element mounted in the handle, a compressible reservoir within the handle, and a resilient member extended through 55 the opening to bear upon the reservoir, one end of the resilient member being adjustably connected with the ink-applying element to permit the resilient member to move freely in the opening. 60

3. A fountain pen structure embodying a handle provided with an opening, an ink applying element mounted in the handle, a compressible reservoir located within the handle, and a resilient member extended 65 through the opening to bear upon the reservoir, there being a slot in the resilient member, and a securing element extended through said slot into engagement with the ink applying element, whereby the resilient member may be adjusted longitudinally of the fountain pen structure, to permit said resilient member to operate freely in the opening. 70

In testimony that I claim the foregoing 75 as my own, I have hereto affixed my signature in the presence of two witnesses.

EDWIN RUTHVEN SMITH.
